UNITED STATES PATENT OFFICE.

ALEXANDER MARSH, OF FLEMINGTON, MISSOURI.

AUXILIARY LOCKING MECHANISM FOR SAFES.

No. 915,617.

Specification of Letters Patent. Patented March 16, 1909.

Application filed April 21, 1908. Serial No. 428,446.

To all whom it may concern:

Be it known that I, ALEXANDER MARSH, a citizen of the United States, residing at Flemington, in the county of Polk and State of Missouri, have invented certain new and useful Improvements in Auxiliary Locking Mechanism for Safes, of which the following is a specification.

This invention relates to auxiliary safe locking devices for preventing unauthorized persons from obtaining access to a safe when otherwise unlocked, and to prevent the door being forced open through the agency of explosives.

With this general object in view, the invention consists in certain novel and peculiar features of construction and organization as hereinafter described and claimed; and in order that it may be fully understood, reference is to be had to the accompanying drawing, in which—

Figure 1. is a vertical section on the line I, I, of Fig. 2, of a safe embodying my invention. Fig. 2. is a vertical section on the line II, II, of Fig. 1. Fig. 3. is an outer face view, partly broken away, of the safe to disclose mechanism hereinafter referred to. Fig. 4. is a section on the line IV IV, of Fig. 3. Fig. 5. is a detail perspective view of a sleeve, hereinafter referred to. Fig. 6. is a detail perspective view of the crank handle for operating the auxiliary locking mechanism.

In the said drawing, 1 indicates a safe of the type shown, or any other suitable type, 35 having the door 2, provided at its inner side with an eye 3. 4 indicates a hook, normally engaging said eye and hinged at its opposite end to a bracket 5, secured to the body of the safe, the arrangement being such that the 40 hook must swing upward to be disengaged from eye 3.

6 is a crank shaft, arranged transversely in the safe, and journaled at its ends in bearings 7, secured to the body of the safe, one end of 45 the shaft projecting through its bearing into an opening 8, of the safe.

9 indicates the crank of the shaft, equipped with a pair of collars or enlargements 10, between which is pivotally mounted on said 50 crank, the front end of a link 11, the said link being preferably of spring metal and secured at its opposite end to a flat sleeve 12, fitting slidingly on hook 4, the front end of 55 said sleeve being provided with a forwardly projecting hook or angle tongue 13, to underlie eye 3 when the hook is engaged therewith,

for the purpose of preventing said hook from being withdrawn from the eye, it being noticed in this connection that when said hooks are engaged with the eye, the crank 9 of the 60 shaft is projecting downward.

The end of the shaft occupying opening 8 is preferably squared, as shown at 14, and projects into the inner end of the tubular hub 15, of a lock casing also occupying opening 8, 65 the lock casing comprising the body portion 16, rigid with said hub, and the face or cover plate 17 secured to the lock plate and normally flush with the contiguous outer face of the safe.

The body portion 16, of the casing is provided with a bearing stud 18, in line with a key hole 19, in face plate 17, and rockingly mounted on said stud within the lock casing is a rock bar or lever 20, provided with an 75 angular socket 21, communicating with the key hole and adapted to receive and be turned by a suitable key, not shown because any object of proper size and rectangular in cross section may be employed as such key. 80 The ends of lock bar 20 have a pin-and-slot connection at 22 with sliding bolts 23, mounted to reciprocate endwise in suitable guides 24, secured to the locking casing, said bolts being adapted to be projected 85 through the casing and into sockets 25, in the adjacent walls of opening 8. It will thus be seen that when the bolts are advanced they lock the casing from sliding inward or outward in opening 8.

26 indicates a key or crank handle, provided with a cylindrical tenon 27, capable of being fitted in the hollow hub 15, but incapable of having its squared socket 28 engaged by the squared end 14, of shaft 6, unless the lock casing has been first pushed inward in opening 8 a sufficient distance, such inward movement being impossible until the bolts 23 are withdrawn, and then occurring under the pressure of the crank handle 100 or key, against the resistance of a helical spring 29, surrounding the shaft and inner end of the hub 15, and bearing at its opposite ends against the lock casing and the adjacent bearing 7. It will thus be seen 105 that the shaft 6 cannot be turned until the bolts 23 have been withdrawn and the lock casing pushed inward, and that to accomplish the turning of the shaft two different keys are necessary. It will be understood 110 that the spring 29 is employed to effect the outward movement of the lock casing, after

the crank handle or key is withdrawn from engagement with shaft 6; and also enables the operator to more quickly dispose the lock casing at the proper point for its bolts 5 23 to enter their sockets 25.

In practice the shaft is turned in the direction indicated by the arrow, Fig. 1, this action through the medium of link 11, first sliding sleeve 12 rearward on the hook 4 10 until hook or tongue 13 is withdrawn from under eye 3. The continued movement of the crank then, through the instrumentality of the link, raises hook 4, the latter being totally withdrawn from the hook by the 15 time the crank 10 attains a horizontal position. The door 2 may then be opened. If it is desired to hold the hook 4 inoperative, the described movement of the shaft is continued until the crank has attained the position shown by dotted lines, Fig. 1, in which 20 position gravity will maintain it, it being noticed that after the crank passes the horizontal plane of its axis in said movement, it slides sleeve 12 forward upon the hook until 25 hook or tongue 13 has attained its original position with respect to hook 4. The movement of the crank shaft is reversed to restore the parts to their original positions, it being understood, of course, that the relocking 30 action is performed after door 2 is closed.

From the above description it will be apparent that I have produced an auxiliary locking mechanism for safes, embodying the features enumerated as desirable, and I wish 35 it to be understood that I reserve the right to make such changes as properly fall within the spirit and scope of the appended claims.

Having thus described the invention, what I now claim as new and desire to secure by 40 Letters Patent is:

1. A locking device for safes, comprising a hook and eye, one adapted to be attached to the door and the other to the safe body, the hook being adapted for pivotal movement, 45 means slidable longitudinally of the hook for normally holding the hook and eye engaged, a crank shaft journaled in the safe, and a link pivotally connecting the crank shaft with said means, and adapted in the initial part of the shaft movement for causing said means to move and leave the hook and eye free to be disengaged, and in a subsequent part of the shaft movement to effect the disengagement of said hook and eye.

50 2. A locking device for safes, comprising a hook and eye, one adapted to be attached to the door and the other to the safe body, the hook being adapted for pivotal movement, means slidable longitudinally of the hook for normally holding the hook and eye engaged, a crank shaft journaled in the safe, and a link

pivotal connecting the crank shaft with said means, and adapted in the initial part of the shaft movement for causing said means to move and leave the hook and eye free to 65 be disengaged, and in a subsequent part of the shaft movement to effect the disengagement of said hook and eye; said link being adapted to restore the movable parts to their original relation when the shaft movement is reversed, in combination with a lock casing, slidably mounted in the body of the safe and provided with a tubular hub, receiving one end of the crank shaft, and with bolts for locking such case rigidly to the safe, to 70 prevent access to the contiguous end of said shaft.

3. The combination with a safe having a door, of an eye movable with said door, a hook hinged to the body of the safe and normally engaging said eye, a hook slidably carried by and movable independently of said hinged hook, and normally engaging the said eye, a crank shaft journaled in the safe, and a link pivotally connecting the crank of said 85 shaft with the said slidable hook.

4. The combination with a safe having a door of an eye at the inner side of said door, a hook hinged to the body of the safe and normally engaging said eye, a sleeve mounted 90 slidably on said hook and provided at its front end with a hook engaging the said eye to maintain the hinged hook in engagement therewith, and means for successively imparting rearward movement to the hook 95 equipped sleeve and upward movement to the hinged hook.

5. The combination with a safe having a door and an opening, of a locking device, comprising a hook and an eye, one adapted 100 to be attached to the door and the other to the safe body, the hook being adapted for pivotal movement, a shaft suitably journaled in the safe and having one end squared and projecting into the said spring, a sleeve 105 mounted slidably on the hook and provided with a hook to engage the eye, a link pivotally connecting said sleeve with the crank of said shaft, a casing fitting slidably in the said opening and provided with an inwardly projecting hub receiving the squared end of the shaft, means for locking said casing rigidly to the body of the safe to prevent said casing being pushed inward to give access to said squared end of the shaft, and a spring 110 for pressing said casing outward.

In testimony whereof I affix my signature, in the presence of two witnesses.

ALEXANDER MARSH.
